CLAIM

The ornamental design for a triangular shaped napkin/-serviette holder, as shown and described.

DESCRIPTION

FIG. 1 is a top plan view of a triangular shaped napkin/-serviette holder showing my new design;

FIG. 2 is a perspective view thereof in a folded position;

FIG. 3 is a top plan view of FIG. 2;

FIG. 4 is a right side elevational view of FIG. 2, the opposite side being a mirror image; and,

FIG. 5 is a front elevational view of FIG. 2, the opposite side being substantially a mirror image.

FIG. 2.

FIG. 3.

FIG. 4.

FIG. 5.
